(57) **CLAIM**

The ornamental design for a two wheeled board, as shown and described.

DESCRIPTION

FIG. 1 is a front, top, left-side perspective view of a two wheeled board of my design;

FIG. 2 is a rear, bottom, left-side perspective view thereof;

FIG. 3 is a top view thereof;

FIG. 4 is a bottom view thereof;

FIG. 5 is a front view thereof;

FIG. 6 is a rear view thereof;

FIG. 7 is a left-side view thereof; and,

FIG. 8 is a right-side view thereof.

The broken lines illustrate portions of the article that form no part of the claimed design.
